REVERSING MECHANISM FOR POWER ENGINES

Alfred Renner, Berlin-Tegel, Germany, assignor to General Electric Company, a corporation of New York

Application February 24, 1933, Serial No. 658,427
In Germany March 10, 1932

2 Claims. (Cl. 123—41)

The present invention relates to reversing mechanisms for power engines such as internal combustion engines in which the fuel supply means including pumps and various valves are 5 operated by push rods or the like moved by means of rotating cams. These cams are fastened to a cam shaft which in the case of a combustion engine is usually driven from the crank shaft.

Reversible internal combustion engines have 10 a cam shaft provided with two sets of cams, one set for operating the valve means for one direction of rotation of the engine and a second set for operating the valve means in the other direction of rotation. The cams with respect to their 15 operation may be termed "forward cams" and "reversing cams". The arrangement is usually such that the forward and the reversing cam for operating a certain push rod are located adjacent each other on the cam shaft. For changing the direction of rotation of the engine the cam shaft or cam holder is moved axially and the push rods are disengaged from one set of cams and brought into engagement with the other set of cams. To permit axial movement of 20 the cam shaft or cam holder it is necessary to move the push rods away from the cams.

One object of the present invention is to provide an improved construction and arrangement of a reversing mechanism for reversible engines 30 of the type specified.

For a consideration of what I consider to be novel and my invention, attention is directed to the following description and the claims appended thereto in connection with the accompanying 35 drawing.

In the drawing, Fig. 1 shows a combustion engine provided with a reversing mechanism in accordance with my invention; Fig. 2 shows a detail view of the reversing mechanism to an enlarged scale; Fig. 3 is a top view of a part of Fig. 2; Fig. 4 illustrates a modification of a reversing mechanism; and Fig. 5 illustrates a top view of a part of Fig. 4.

The combustion engine shown in Fig. 1 comprises a frame 10 containing a cylinder and a cylinder head 11 with a valve 12. The valve 12 may serve for regulating the supply of fuel to the cylinder head 11 or the discharge of burned gases from the cylinder. The valve is moved by 40 a fulcrumed lever 13 which has one end pivoted to a push rod 14 carrying at its lower end a roller 15. The roller 15 engages in its operative position (see Fig. 2) a cam 16 fastened to a cam shaft or cam holder 17 which in turn is supported by a bearing 18. During normal operation the cam 16 rotates to force the push rod 14 upward, thereby 45 actuating the valve 12. The push rod 14 may be forced downward to maintain its operative 50 relation with the cam by means of a spring, (not

shown), which usually forms a part of the valve 52.

The arrangement so far described serves for operating the engine in one direction of rotation. To permit operation in the opposite direction of 5 rotation, a second cam 19 is fastened to the cam shaft 17 and means are provided for changing the cooperative relation between the cams 16 and 19 and the roller 15. The reversing of the engine, that is, the change of the cooperative 10 relation between the cams and the roller is accomplished in accordance with my invention by a mechanism which by the single actuation of a certain element removes the roller from the forward cam and brings it into engagement with the 15 reversing cam.

The reversing mechanism shown in Figs. 1 to 3 comprises a link 20 which is pivoted at 21 to the lower end of the push rod and at 22 to another link 23. The latter is fastened to a regulating shaft 24 together with a link 25 which in turn is pivoted at 26 to a follower 27. The follower 27 is pivoted at 28 to a curved disk or positive action cam 29 fastened to a shaft 30. The disk comprises three outer portions (Fig. 3), 25 a plane portion *a*, a curved portion *b* and another plane portion *c*. The bearing 18 is slidably arranged on a support 31, in the present instance shown as having a dovetail connection 32 with the bearing 18. This dovetail connection prevents vertical and sidewise movement of the bearing but permits axial movement thereof. The rim of disk 29 engages two rollers 33 and 34 fixed to the bearing. With this arrangement, turning 30 of the disk 29 causes axial movement of the bearing as soon as the curved outer portion *b* of the disk or cam is moved between the rollers 33 and 34. Movement of the bearing in turn causes 35 axial movement of the cam shaft, relative movement between the latter and the bearing being prevented by the provision of rings or collars 35, 36 fastened to the shaft 17. A pinion 37 (Fig. 1) fastened to the shaft 30 meshes with a rack 38 connected to the piston 39 of a hydraulic motor. 40 The latter comprising a cylinder 40 and a pilot valve 41 having a valve member 42 connected to a fulcrumed hand lever 43. The pilot valve has ports 44 for supplying actuating fluid to the cylinder and a port 45 for draining actuating fluid 45 from the cylinder. In the position indicated in the drawing, actuating fluid is supplied to the left-hand portion of the cylinder and drained from the right-hand portion thereof, to the effect 50 that the rack is moved to the right and the disk or cam 29 turned in counter-clockwise direction. If the position of the pilot valve is reversed, a 55 similar operation takes place but in the opposite direction, resulting in movement of the disk or cam in clockwise direction. The hydraulic mo- 60

tor, together with the pilot valve, represents in substance a reversible motor or a power agency for operating the reversing mechanism.

The motion of the links and the follower during the reversing of the mechanism comprises two parts or steps. During the first part the roller 15 is moved away from the cam 16, for example, and during the second part the roller 15 is returned and brought into engagement with the cam 19. 5 In Fig. 2, "I" indicates the position of the link mechanism while the roller 15 engages cam 16, and "II" the position of the links and the follower at the end of the above mentioned first part of the motion; the movements have been indicated 10 by arrows. During the second part of the motion the links are merely returned from the position "II" into position "I", whereas the follower 21 assumes a new position "III" in accordance with the changed position of the cam 29. 15

20 In Fig. 1 I have shown the reversing mechanism in the intermediate position, that is, at the end of the first part of the reversing motion.

Thus it will readily be seen that turning of the disk 29 causes removing of the roller 15 from the cam shaft and thereafter returning of the roller 15 to the cam shaft. While the roller 15 is being moved away from and returned to the cam shaft, the latter itself is moved or shifted in axial direction. More specifically, with the arrangement shown in Figs. 1, 2 and 3, the axial movement of the cam shaft or cam holder takes place approximately during the second half of the first part of the link motion and during the first half of the second part thereof. No axial movement of the cam shaft takes place as long as the plane portions *c* and *a* are moved between the rollers 33 and 34 of the bearing. Axial movement of the bearing is caused only while the portion *b* of the disk 29 is moved between the rollers 33 30 and 34. Furthermore, the connection between the follower 27 and the cam 29 is such that turning movement of the latter does not effect axial movement of the link mechanism (see Fig. 3). In Figs. 4 and 5, where I have shown a modification 35 in accordance with my invention, a push rod 50 carries a roller 51 which engages a cam 52 fastened to a cam shaft or cam holder 53. The latter is supported by a bearing 54 having a 40 slide support 55. Pivoted to the push rod is a link mechanism comprising links 56, 57 and 58 corresponding to links 20, 23 and 25 respectively in Figs. 1 to 3. The links 57 and 58 are fastened in fixed relation to each other on a regulating shaft 59. Whereas link 25 in Figs. 1 to 3 is fastened to a follower 27 moved by a disk 29, I provide in the arrangement of Figs. 4 and 5 the link 58 with a roller or pin 60 located and positively moved in a groove 61 in the face of a cam or cylinder 62, that is, I substitute for the follower 45 50 55 60 65 70 75 27 in Figs. 1 to 3 the groove 61 of the cam 62 in Fig. 4. The cylinder 62 is fastened to a rotatable shaft and has on its cylindrical surface a groove 63. A roller 64 carried by the bearing projects into the groove 63 of the cylinder 62. With this arrangement, rotative movement of the disk 62 causes axial movement of the bearing, disengagement between roller 51 and cam 52, and engagement of roller 51 with a cam 65 located adjacent cam 52. The center lines of the links 57 and 58 in the operative position of roller 51, that is, in the position in which the roller engages one of the cams, are designated by "I" and in the intermediate position, that is, the position reached at the end of the first part of the link and cylinder motion is designated by "II". The cylinder

62 represents a positive action cam, more specifically a face cam with regard to the action of groove 61 and a cylindrical cam with regard to the action of groove 63 or with respect to the actions of both grooves the cam forms a combined face and cylindrical cam. 5

With my invention I have accomplished an improved construction and arrangement for a reversing mechanism particularly suited for reversible internal combustion engines. The reversing operation is effected by the actuation of a power agency and means which link the sidewise movement of the roller with the axial movement of the cams so that it cannot happen that for instance the cams are moved axially before the 15 roller has been moved a sufficient distance away from the cam shaft. It requires no skill to reverse a combustion engine provided with my mechanism.

Having described the method of operation of 20 my invention, together with the apparatus which I now consider to represent the best embodiment thereof, I desire to have it understood that the apparatus shown is only illustrative and that the invention may be carried out by other means. 25

What I claim as new and desire to secure by Letters Patent of the United States, is:

1. In a reversible internal combustion engine, the combination of a cylinder, provided with a cylinder head, a cam shaft, two cams on the 30 shaft, a slide bearing having a casing supporting the shaft, a valve actuating means including a push rod and a roller engaging one of the cams, and means disposed substantially below the cylinder head for reversing the engine 35 comprising a single positive action cam having a portion engaging the casing of the bearing, a rotatable straight shaft member mounted on the side of said cylinder below said cylinder head and provided with a pair of arms, a link pivotally connected at one end to one of said arms and at the other end to said push rod, and a second link pivoted at one end to the second of said arms and at the other end to the positive action cam whereby movement of the positive action 45 cam effects axial movement of the bearing with the cam shaft and simultaneously removing of the roller from one cam and returning of the roller into engagement with the other cam.

2. In a reversible internal combustion engine, 50 the combination of a cylinder having a head, a cam shaft, a bearing supporting the shaft and having a casing with two projections, means preventing relative axial movement between the bearing and the shaft, a support for the bearing 55 permitting sliding movement of the latter, two cams on the shaft, a push rod having a roller at its lower end engaging one of the cams, and means for reversing the engine comprising a positive action cam extending between the projections on the bearing casing, a link mechanism pivoted at one end to the positive action cam and at the other end to the push rod and means including a hydraulic motor and a gear connected to the positive action cam and operated by the 60 motor to cause axial movement of the bearing with the shaft and simultaneously removing the roller from one cam and engaging it with the other cam, the reversing means being disposed at 65 the side of said cylinder and below the cylinder head to permit easy removal of the cylinder head without necessitating disassembly of the reversing mechanism. 70
